UNITED STATES PATENT OFFICE.

CLAUDE S. WILLEY, OF DETROIT, MICHIGAN.

SIGN AND MEANS FOR MOUNTING THE SAME.

Application filed April 1, 1927. Serial No. 180,146.

This invention relates to a sign and means for mounting the same.

The invention is directed particularly to a sign adapted to be illuminated in its interior so as to render indicia visible. The sign may be provided with glass panels and the indicia may be painted, sand blasted or otherwise fixed on the glass panels.

In signs of this character, such as elevator signs, or the various signs in a theater, it is desirable to sometimes have the sign project outwardly from a wall or other support so that the sign can be read from both sides thereof. This is known as the projecting type. Sometimes it is desirable to have such a sign lie flat against a wall or other support, so that the sign is visible to one who is a distance away from the wall and looking towards the wall. This is a wall type. In this last mentioned case it is, of course, necessary to have the indicia only on the one side of the sign because the side that faces the wall is not visible and may be blank.

The present invention aims to provide a sign structure and a support therefor which are arranged so that the sign can be installed to lie against the wall or project outwardly therefrom and the arrangement is such that a sign which has been installed as a projecting type can be readily switched to the wall type or vice versa without involving any structural changes and with a minimum outlay of time and labor.

In the accompanying drawings Figure 1 is a perspective view of the sign support.

Fig. 2 is a sectional view taken on line 2—2 of Fig. 1.

Fig. 3 is a view showing the support secured to a wall and showing a sign secured to the support and projecting outwardly from the wall.

Fig. 4 is a view similar to Fig. 3 showing how the same sign is held by the support by converting it into a wall type of sign which is distinguished from the projecting type in Fig. 3.

Fig. 5 is a perspective view of a modified form of support.

The sign support takes the form of a sheet metal member 1, and the edges of the member may be turned inwardly somewhat as shown at 2 to add to the appearance of the support and it may be otherwise suitably decorated or colored. Near its upper end the sign is provided with openings 3 and 4, and near the

lower end it is provided with openings 5 and 6. The support is designed to be placed against a wall and secured thereto as by means of wood screws 7 which are taken through these openings.

The support is provided with a further set of openings 8 and 9 near its upward end, for the purpose of securing the sign structure thereto as will presently appear. Where the sheet metal of the member is quite thin, nuts 10, which are internally threaded, may be secured to the rear of the openings 8 and 9 for the purpose of receiving screws. The openings 8 and 9 may be threaded if the metal is of sufficient strength and thickness to permit. Near the lower end of the support there is a projection or stud 11 which is fixed to the sheet metal member as by means of soldering or riveting. As shown in Fig. 5, this may be done by cutting out a piece of the metal as shown at 11^a and then bending this piece of metal outwardly as shown.

By reference to Figs. 3 and 4 it will be noted that the sign comprises a casing having panels 15 and 16, and the casing includes a moulding 17 which provides a light compartment. The top of the casing is closed by a cover 18 which carries an electric light bulb. With a sign of this character the moulding at the top projects outwardly from the main body of the sign casing equally on all sides.

The moulding part of the sign is provided with openings 20, in one end which corresponds with the openings 8 and 9 in the support, and with the cover 18 removed, machine screws 21 are taken through openings 20 and into the nuts 10. The projection 11 or 11^a extends outwardly from the support a distance which is equal to the width of the moulding. The lower end of the sign structure meets this projection so that the sign is held in a vertical position relative to the wall.

In order to convert the sign from the projecting type to the wall type, it is mounted as shown in Fig. 4 the moulding being provided with openings 22 in one side thereof which correspond to the openings 8 and 9 to the support and machine screws 21 are taken through the openings into the nuts 10. It will be understood that the sign can be mounted either way originally and may be changed from one position to another at any desirable time.

A sign structure which is nicely adapted for use with such a bracket is described in a

copending application Serial No. 180,735. The sign structure need not be described here in detail and suffice it to say that the panels 15 and 16 are preferably glass provided with suitable indicia. These panels are spaced apart by combined reflectors and holding elements 25. These holding elements are placed along the three edges of the panels other than the edge adjacent to the light compartment. Adjacent the light compartment, however, U shaped strips of metal 26 are placed so as to securely hold the upper edges of the panels to the adjacent part of the sign casing. With this structure the panels 35 and reflectors and all parts within the casing are placed therein without involving any soldering or similar operation and the panels and other elements are easily assembled, removed, and changed. Thus it is that when 20 the sign is used as a projecting type both panels 15 and 16 may show sign matter. When the sign is used as a wall type one panel may be removed if desirable, and a blank panel of glass, or of cheaper material 25 such as sheet metal may be used instead.

By the use of this invention not only is the utility of the sign structure enhanced, but the manufacture of signs is made easier. Heretofore it has been necessary to make two 30 entirely different sets of signs, one the projecting type and one wall type, in that they were not convertible, i. e. a wall type could not be satisfactorily used as a projecting type and vice versa. The present invention makes 35 it possible to manufacture a single type of sign which can be sold and used either as a projecting or wall type to meet the requirements of any particular installation.

Claims:

- 40 1. In a sign, the combination of a sign structure having a moulding extending around all of its sides, of a sign support provided with means for securing the moulding thereto, means projecting from the support 45 and equal to the width of the moulding and abutting against the sign at a point other

than at the moulding, whereby a sign may be secured to the support at any one of its sides.

2. In a sign, the combination of a sign 50 structure having a moulding at its upper edge and having a sign panel visible at opposite sides thereof, a support for the sign having means at one end for the seaming of the moulding, means at its other end which projects outwardly equal to the width of the moulding and against which the sign, when mounted, is adapted to rest, whereby the sign may be mounted at one end to project 55 outwardly from the wall or mounted at one side to lie parallel with the wall.

3. In a sign, the combination of a sign structure having a top moulding and one or more sign panels, a support for the sign structure adapted to be secured to a wall or 60 the like, said support having near its upper end means for the securing of the moulding hereto, and having near its lower end a projection equal to the width of the moulding 65 whereby the sign structure may be mounted 70 as a projecting type or wall type of sign as elected.

4. In a sign, the combination of a sign structure having a top moulding which constitutes a light compartment and also having spaced sign panels adapted to show sign matter in opposite direction, said panels being illuminated from the light compartment, a support for the sign adapted to be fixed to a wall or the like, said support, near its upper 75 end, having means for the securing of the moulding of the sign structure thereto, said support having a projection near its lower end which extends outward from the support 80 equal to the width of the moulding and which forms a rest for the sign structure whereby the sign structure can be secured to the support either at one of its ends or one of its 85 sides.

In testimony whereof I affix my signature.

CLAUDE S. WILLEY.
